UNITED STATES PATENT OFFICE.

EMIL BAUMANN, OF ST. LOUIS, MISSOURI.

AIR-SHIP.

No. 854,555.

Specification of Letters Patent.

Patented May 21, 1907.

Application filed October 3, 1906. Serial No. 337,293.

To all whom it may concern:

Be it known that I, EMIL BAUMANN, a citizen of the United States, residing at St. Louis, in the State of Missouri, have invented 5 new and useful Improvements in Air-Ships, of which the following is a specification.

This invention relates to aerial navigation and one of the principal objects of the same is to provide an air ship with rotatable aeroplanes carrying each a series of pivoted and balanced vanes, whereby the same may be 10 presented at various angles to the wind for propelling and steering the ship.

Another object of my invention is to provide 15 an airship, made buoyant by a gas bag, with oppositely disposed aeroplanes each carrying a series of balanced vanes and both of said aeroplanes being rotatable in the same direction and adjustable at various angles to control the direction of the ship..

These and other objects may be attained by means of the construction illustrated in the accompanying drawing, in which:

Figure 1 is a side elevation of an airship 25 made in accordance with my invention. Fig. 2 is a front elevation of the same. Fig. 3 is a side elevation similar to that shown in Fig. 1 with the aeroplane in a different position. Fig. 4 is a detail, perspective view of one of 30 the vanes partially broken away.

Referring to the accompanying drawings for a more particular description of my invention, the numeral 1 designates an ordinary balloon or gas bag connected by means 35 of cords or ropes 2 to cross bars 3 secured to the frame 4 of the airship. The frame 4 comprises oppositely disposed side pieces which may be cut away to reduce their weight and a boat-like basket or hull 5 suspended from 40 the lower edges of said frame members. Mounted to rotate in the frame 4 are oppositely disposed cranked shafts 6, said shafts each having a horizontally extending member 7 upon each of which is pivoted an aeroplane 8. Pivotaly mounted in the aeroplane 8 is a series of vanes 9, each comprising a light frame 10 into which is properly stretched a silk or other diaphragm 11, said vanes having outwardly projecting pintles 12. 45 disposed above the horizontal center of said vanes in order that they may always assume a vertical position when the aeroplanes are moving in an upward direction. When the aeroplanes move downward the impact of 50 the air is sufficient to move said vanes into a horizontal position.

Secured to the upper edge of the frame 10 is a ball or weight 13 from which a shank 14 extends to the frame 10, as shown more particularly in Fig. 4. A sprocket chain 15 is 60 connected at its ends to the outer ends of the aeroplane 8 and said chain passes around a sprocket wheel 16 mounted upon the end of a shaft 17 which is provided with a hand wheel 18 for adjusting the aeroplane in various angular positions for a purpose which will 65 presently appear.

To hold the aeroplanes in adjusted position, a pawl and ratchet 19 is provided. The shaft 17 is mounted in a rotatable frame 70 20, the shaft 21 of which is journaled in the frame 4. A sprocket wheel 23 is carried by the shaft 20 and around this wheel passes a sprocket chain 24 which leads to a sprocket wheel 25 on the shaft of the motor 26. It is 75 to be noted that there are two motors 26 which may be of the gasoline type or of other suitable character and that the arrangement of aeroplane and vane is substantially identical upon opposite sides of the 80 frame; hence a description of one will serve for both. The shaft 6 is provided with a horizontal member 6^a which extends through the frame 4 and is journaled in the bracket 6^b secured to the inner wall of the frame 4. 85 A sprocket chain 27 extends around sprocket wheels 28 secured to the member 6^a of the shaft 6, said sprocket chain extending around sprocket wheels 29 on the shaft 21, and the upper stretch of said sprocket chain extending in an inclined direction and passing around a sprocket wheel on the shaft 30.

From the foregoing it will be understood that the aeroplanes upon opposite sides of the machine are simultaneously rotated. 95

The operation of my invention may be briefly described as follows: The balloon or gas bag 1 may be assumed to have sufficient capacity to sustain the weight of the entire ship but need not be sufficient to ascend 100 without the use of the aeroplanes and vanes. The motors 26 being started, the aeroplanes 8 are rotated upon their axes in the direction indicated by the arrows in Fig. 1 to carry the ship upward. The aeroplanes may be inclined independently by means of the hand wheels 18, the vanes assuming a vertical position by means of the construction described. When it is desired to descend, the aeroplanes 8 are adjusted to the required angle of 105 inclination to steer, propel, ascend, and descend, as will be understood. The vanes 110

9 being properly balanced by means of the weight 13 at the upper side of the vane frame are more responsive to the action of the air than would be the case if the weights 5 13 were omitted and the air alone serving to actuate said vane.

From the foregoing, it will be obvious that an airship made in accordance with my invention and provided with a buoyant bag or 10 sack containing sufficient gas to poise the ship will permit the aeroplanes and vanes to control the ascension and direction thereof without having to overcome the weight of the ship.

15 Various changes in the details of construction may be resorted to without departing from the spirit and scope of my invention.

Having thus described my invention, what I claim is:

20 1. An air ship comprising a buoyant medium of just sufficient capacity to sustain the weight of the entire air ship, a frame connected to said buoyant medium, crank shafts

mounted in said frame, aeroplanes pivotally mounted on said crank shafts, weighted 25 vanes pivoted to the aeroplanes and hand wheels for adjusting the inclination of said aeroplanes.

2. An air ship comprising a buoyant bag, a frame to which said bag is connected, crank shafts journaled in said frame, aeroplanes pivotally connected to said shafts, weighted vanes pivotally connected to said aeroplanes, drive chains connected at their ends to said aeroplanes, a shaft carrying a sprocket wheel 35 engaging said chain, a ratchet wheel upon said shaft, a hand wheel on said shaft, a rotatable frame to which said shaft is journaled, and means for rotating said aeroplanes, substantially as described.

40 In testimony whereof, I affix my signature in presence of two witnesses.

EMIL BAUMANN.
